PAPER BOTTLE

Filed May 29, 1926

UNITED STATES PATENT OFFICE

ARLINGTON MOORE, OF NEW YORK, N. Y.

PAPER BOTTLE

Application filed May 29, 1926. Serial No. 112,486.

This invention relates to paper containers, or bottles and more particularly to those of a type having a permanently attached swivel top which is provided with a port, through which the contents of the receptacle may be poured, when the cap is moved into a position to bring the port into register with a corresponding port in the neck of the bottle.

More specifically, the present invention relates to certain improvements on the type of bottle shown in my pending application Serial No. 507,371, and has for its object to simplify the constructions of said prior devices, and to produce a construction which will be at least as durable and rigid as said prior devices and which may be constructed by tools which are less complicated than those necessary for the production of said prior devices.

20 A further object of the present invention is to provide an improved body construction which will be practically seamless, so that all danger of leakage will be avoided and the side wall of the container will be of uniform thickness at all points, whereby a perfectly cylindrical or conical surface may be provided between the wall and the cap which rotates thereon, so that the cap may seat tightly thereon and still have the desired freedom 30 of rotation.

For a more complete understanding of my invention reference is made to the accompanying drawings in which Fig. 1 is a view, partly in elevation, and partly in central longitudinal section, of a preferred form of my invention. Fig. 2 is a transverse sectional view on the line 2—2, Fig. 1. Figs. 3 to 6 inclusive are detail sectional views of portions of the side wall. Figs. 7, 8 and 9 are detail sectional views illustrating successive 40 steps in the operation of forming the cap and its swivel connection with the body.

As shown in the drawing, the side wall 1 of the container tapers uniformly from top to bottom, and is preferably formed by winding a sheet of the paper stock, which has been cut out to form a suitably shaped blank, onto a conical mandrel, the contour of the blank being such that, when it is wound thereon, 50 two complete plies of the stock will be formed

about the same, so that the end edges 1^a, and 1^b will be substantially opposite each other, or at opposite sides of the middle portion of the sheet, as shown in Fig. 3. The plies of stock, as thus convoluted, are subjected to a very high pressure between conical male and female dies, so that the end portions of the blank, which are at the inner and outer sides of the intervening portion of the sheet, will be pressed toward one another until their inner and outer surfaces are flush with the inner and outer surfaces of the adjacent middle portion of the sheet, thereby pressing the portion of the sheet, which is initially held out of contact with the surface of the dies by the inner end portion of the sheet, into contact with said die surfaces and causing two right angular bends, or two oppositely disposed shoulders to be formed in the intervening sheet portion, as it extends between the ends of the sheet, and against which the edges 1^a, 1^b abut. The inner surface of the inner end portion and the outer surface of the outer portion are thus made continuous with the respective inner and outer surfaces of the adjacent sheet portions, as shown in Fig. 4. It will be observed that, as thus formed, the thickness of the side wall will not, at any point, be either greater or less than two plies of the stock. The stock also extends practically continuously between the ends of the blank and the intermediate portion thereof, as said ends are pressed with great force into contact with the surfaces with which they abut, so that they are practically welded thereto.

As shown in Fig. 5, the blank may be of such length that its end portions 1^c and 1^d slightly overlap, in which case, when the pressure is applied, the bends which are formed in the sheet, as it passes between its ends, will not be as sharp as those shown in Fig. 4 and the end portions of the blank will be pressed into a somewhat tapering form, as indicated at 1^e in Fig. 6. In this instance the stock will be somewhat more highly consolidated at the points where there are slightly more than two plies of stock, so that the end portions of the blank will be more securely welded to the adjacent surfaces of the

portions of the stock which they overlap, than in the construction illustrated in Fig. 4. In practice, the construction last described is considered somewhat more desirable than the other, as the slight amount of excess stock beyond two plies is distributed, or pressed back into the adjacent portions of the stock, so that there is no actual increase in the thickness of the stock at any point, while the welding of the end portions to the middle portions is more effectively performed.

As blanks cut from the same pattern, or die, may vary slightly in length at different times, due to changes in humidity of the atmosphere, these variations will be compensated for by the high pressure to which the overlapping portions are subjected.

In the operation of forming the side wall, an internal shoulder 2 is formed against which a bottom 2^a of stiff board is secured, said bottom being inserted after filling and held in place by bending or rolling the rim portion 2^b inward and pressing it thereagainst, in a manner similar to that described in connection with the sealing of the closure, in my application Serial No. 454,770.

In the formation of the cap and its swivel connection with the side wall, the conical shell 3 and the cap 4, having the edge-flange 5, are assembled therewith in a manner similar to that described in my pending application, Serial No. 507,371, the conical shell being inserted in the conical side wall, so that it seats tightly in its smaller end, and a port 6 is formed therein, in such a position that it registers, or is in a position to register, when rotated, with a port 7 in the side wall. The cap 4 is forced into the shell 3, so that its flange 5 extends outwardly therein, in close engagement therewith, the relative positions of the side wall, shell and cap, before the folding operation is begun, being indicated in Fig. 7. It is to be especially noted that the side wall 1 terminates at 1^f on a line between the body part 4^a of cap 4 and the edge 5^a of its flange 5, the extremity 1^f of body wall 1 overlapping the flange 5 for about one-fourth of the distance from the body part 4^a of cap 4 to the edge 5^a of the flange 5, and that the shell 3 extends beyond the edge 5^a of the flange 5 a distance somewhat greater than the length of the flange. The operation of folding these parts together is as follows:

The shell 3 is folded inward to such a point that its terminal portion 3^a overlaps the terminal portion 5^a of the flange 5 for approximately one-third the length of the latter, the line 3^b at which the shell 3 is folded reversely being at a distance from the edge of the flange 5 equal to about one-third of the length of the latter. The position of the parts at the end of this part of the operation is indicated in Fig. 8. This and the following part of the operation, described below, may be and

preferably are substantially continuous but are best understood by being divided into component stages for their description. As thus arranged, the flange 5, with the terminal portion 3^a of the shell extending reversely on its inner surface, is then bent inward at the line 3^b where the shell terminates thereon, so that the outer surface of the terminal portion 3^a is laid in contact with the inner surface of the flange 5 from the point where the flange was bent inward to the body part 4^a of cap 4, in which position the points at which the shell was folded by the first operation will be brought into contact with the body part 4^a of the cap 4, the position of the parts at the end of this operation being indicated in Fig. 9. It will be noted that, as thus folded, there will be four thicknesses of the material lying within the seam, from the body part 4^a of cap 4 to the end of the side wall, and five thicknesses of material beyond the end of the side wall.

In the next part of the operation, by means of suitably shaped dies, the various folds, above described, are pressed outward by a high pressure, against a conical mold surface, which corresponds to the outer surface of the side wall, and extends continuously beyond the end of the side wall, so that the folds beyond the end of the side wall are pressed outward until the outer surface of the shell portion between the end of the side wall and the point where the shell is bent inward with the flange is continuous with the outer surface of the side wall, a sharp outward bend or shoulder 3^c being formed in the shell against which the end of the side wall abuts, as shown in Fig. 1, in which the finished structure is shown (thickness of parts being more or less exaggerated).

At the same time that the folds are pressed transversely, or outwardly, as above described, they are pressed longitudinally to form a flat rim portion 3^b, and the portion of the shell, at the region 3^b where it is bent reversely to form the terminal portion 3^a, is pressed against the body portion 4^a of cap 4, the mass being thus firmly compacted, so that the contacting surfaces are practically welded together into a solid mass, by reason of the high pressure to which they are subjected, forming a liquid tight connection between the shell and cap. The compacting and welding of the side seam of body wall 1 may be performed at this time, it being understood that the closure 2 is not inserted until later when the container is filled and sealed.

Upon the completion of the operation with the parts related as indicated in Fig. 1, the tapering shell 3, which is now practically integrally connected with the cap, is held in close contact with the correspondingly tapering inner surface of the side wall, or is seated thereon, so as to make a liquid tight connection therewith, by its shoulder 3^c, which en-

gages the end of the side wall, so that a swivel connection between the cap and side wall is provided, permitting the cap to be rotated, so as to bring the ports 6 and 7 into register. It will be noted that, when finished, the ring like seam formed by folding together the end portions of the shell and the cap flange is of uniform thickness, except at the point where it is overlapped by the side wall, the latter supplying the difference of the extra fold, so that the inner surface 8 of the seam ring is parallel with its outer surface 9.

I claim:

1. A paper container comprising a multiply tubular body portion having the intermediate portion of the blank contiguous to the end portions thereof provided with an off-set forming shoulders at the opposite sides of the offset abutting said end portions; said intermediate and end portions being consolidated together under high pressure to form a body portion of substantially uniform thickness throughout having substantially smooth continuous inner and outer surfaces.

2. A paper container comprising a two-ply, tapered, tubular body portion having the intermediate portion of the blank contiguous to the end portions thereof provided with an off-set forming shoulders at the opposite sides of the offset abutting said end portions; said intermediate and end portions being consolidated together under high pressure to form a body portion of substantially uniform thickness throughout having substantially smooth continuous inner and outer surfaces.

3. In a paper container, a tapered sidewall having a smooth, continuous inner surface, a swiveling closure therefor comprising a tapered shell having a skirt fitting in and projecting from the smaller end of the sidewall and having an opening adapted on rotation of the shell to register with an opening in the sidewall, and a flanged cap, the shell and cap flange being interlocked inwardly and consolidated into a ring-like seam, said seam being provided with an exterior shoulder and the edge of the sidewall being terminated against said shoulder and between the top and the bottom of said seam.

4. A tapered paper container sidewall, a tapered shell inserted therein to project from the smaller end thereof, a flanged cap, a reinforced marginal rim formed by interfolding and consolidating said shell and cap flange and having an outer shoulder intermediate the upper and lower edges thereof, the edge of the sidewall at its smaller end receiving the lower part of said rim and being received against said shoulder, whereby the inserted shell is held in close contact with the sidewall, and shell and sidewall having corresponding ports adapted to be brought into register upon rotation of the shell in the side wall.

5. In a container, a tapered sidewall member, a tapered shell extending from the smaller end of the tapered sidewall member, a flanged closure for said shell, an interfolded and consolidated seam formed from said shell and closure flange, said seam having one part comprising five thicknesses, of the component material and another part of four thicknesses, with an exterior shoulder between these two parts, and the sidewall member projecting past the body part of the closure into contact with said shoulder for substantially the extent of the four thickness part of the seam rim, thereby substantially making this part too of five thicknesses, and corresponding ports provided in sidewall and shell and adapted to register upon rotation of the shell.

6. A paper container having its sidewall extended to form a conical, tapering neck portion, a closure for said neck comprising a correspondingly tapering shell seated against the inner surface of the neck and extending beyond the end thereof, and a flanged end wall member disposed in said shell and having its body part located within the neck at a substantial distance from the end thereof and its flange in engagement with said shell, both said flange and shell being extended laterally to form an intermediate shoulder for engagement with the end of the neck to hold the shell in seating engagement with its inner surface, said flange and shell portions, beyond said shoulder, being bent inward and extended reversely to form overlying folds and said folds being pressed together to form a reinforcing rim, said neck and shell portions having corresponding ports arranged to be brought into registering position upon rotation of the closure.

7. In a tapered paper bottle, a sidewall, a swiveling closure therefor having a multi-ply seam ring having one more thickness at its upper than at its lower end to provide an exterior recess about the lower portion of said seam ring for receiving said side wall, the sidewall extending outside of and encircling that part of the seam ring having the reduced number of plies in its thickness.

8. In a paper bottle, a tapered side wall having a smooth continuous inner surface, and a swiveling closure therefor comprising a skirt having a hole adapted to register with a hole in the sidewall, and a flanged dish inserted in said skirt, said skirt and flange being repeatedly folded inwardly and consolidated into a dense, strong, ring-like seam with an outer downwardly facing shoulder located at approximately mid-height of the seam, the edge of the side wall surrounding the lower part of said seam and terminating against said shoulder.

In testimony whereof, I have signed my name hereto.

ARLINGTON MOORE.
